UNITED STATES PATENT OFFICE.

VICTOR ROSENHAGEN, OF NEWPORT, KENTUCKY, ASSIGNOR OF ONE-HALF TO ARTHUR C. HALL, OF NEWPORT, KENTUCKY.

INTERNAL-COMBUSTION ENGINE.

1,168,425.

Specification of Letters Patent. Patented Jan. 18, 1916.

Application filed February 28, 1915. Serial No. 9,836.

To all whom it may concern:

Be it known that I, VICTOR ROSENHAGEN, a citizen of the United States of America, and resident of Newport, county of Campbell, State of Kentucky, have invented certain new and useful Improvements in Internal-Combustion Engines, of which the following is a specification.

This invention relates to improvements 10 in internal combustion engines and particularly to internal combustion engines of the two stroke cycle type. Internal combustion engines which operate upon the well known two stroke cycle principle, are ordinarily 15 constructed so that admission of the fresh charge occurs simultaneously with the exhaustion of the products of combustion. This results in a portion of the fresh charge being exhausted with the products of combustion before this portion of the fresh charge can be utilized. In addition to this the two stroke cycle engine as ordinarily constructed, is one which, because of this simultaneous occurrence of the exhaustion 20 of the products of combustion and the admission of the fresh charge, is liable to and frequently does result in premature ignition or back fire of the incoming fresh charge. Such an occurrence is decidedly 25 objectionable in that a loss of fuel not only results, but there is also danger of a resultant back fire into the carburetor, which frequently causes the carburetor to catch fire with disastrous results. Furthermore, 30 two stroke cycle engines as ordinarily constructed are more or less inefficient in operation since comparatively too short a time is allowed in which exhaustion of the products of combustion may take place. This 35 results in a relatively great proportion of the products of combustion, remaining in the cylinder after the exhaust port has been closed, and for this reason does not permit a sufficiently large amount of fresh fuel to 40 occupy the engine cylinder to bring up the engine power to the amount it should normally have.

It is therefore, an object of my invention to produce a two stroke cycle internal combustion engine which is so constructed that there can be no waste of the fresh charge of fuel.

A further object of my invention is to produce a two stroke cycle internal combustion engine in which premature explosion caused by the fresh charge of fuel coming in contact with the burning products of combustion, is rendered impossible.

A further object of my invention is to produce a two stroke cycle internal combustion engine in which the cylinder is thoroughly scavenged of the products of combustion before admission of each charge of fresh fuel.

These and other objects are attained in 65 the engine described in the following specification and illustrated in the accompanying drawings in which;

Figure 1 is a longitudinal sectional view of an engine embodying my invention. Figs. 70 2 to 10 inclusive are views illustrating the engine in a somewhat diagrammatic manner and showing the positions occupied by the various parts of the engine during the operation thereof.

The engine embodying my invention consists of a power cylinder 11 and a supply cylinder 12 both of which are mounted upon and secured to a crank case 13. A piston 14 is located in the power cylinder 11 and is 80 connected by means of a connecting rod 15 with a fly wheel 16 mounted in the crank case. A piston 17 is located in the supply cylinder 12 and is connected by means of the connecting rod 18 with a pin 20^a mounted in a lug 19 formed on the connecting rod 15. By means of this construction the crank pin 20 to which the crank end of the connecting rod 15 is secured, acts as a common crank pin for both connecting 90 rods 15 and 18.

At the top of the supply cylinder an inlet valve 21 is secured, the valve being mounted in a casing 22 secured to the head of the cylinder, and adapted to communicate with a suitable gas producing apparatus, such as a carburetor. In the head of the power cylinder a spark plug 23 is located for the purpose of exploding each fresh charge of fuel in the power cylinder. 100 On one side of the power cylinder and located in a casing 24 formed between the supply and power cylinders, is an auxiliary inlet valve 25 which is adapted to coöperate

with the supply cylinder in admitting a charge of fuel into the power cylinder. On the opposite side of the power cylinder is located a valve 26 which reciprocates in a casing 27 formed integrally with the cylinder. In the crank case 13 is located an air inlet valve 28 which is adapted to permit air to enter the crank case, but to prevent air from leaving the crank case through the 10 valve.

The supply cylinder is provided with a by-pass port 29 which coöperates at its lower end with the upper end of a by-pass port 20 formed in the wall of the supply piston 17. A port 31 located between the supply and power cylinders, coöperates with the by-pass port 30 formed in the wall of the piston 17 and communicates with the valve chamber 32 in which the auxiliary 15 inlet valve 25 reciprocates. Chamber 32 in turn communicates with a port 33 opening into the power cylinder adjacent to the end of the cylinder. The valve 25 which reciprocates in the chamber 32, is provided at 20 its upper end with a sleeve 34 adapted to close the port 33 so that no gas can pass into the chamber 32, and the head 35 of the valve is adapted to stop communication between the chamber 32 and the port 31.

30 The power piston 14 is provided at its upper closed end with a deflector 36 which is located adjacent to the wall of the piston and which is adapted to deflect the incoming fresh charge to the top of the cylinder. In 35 the wall of the power cylinder and at its lower end is a by-pass port 37 which operates to permit air from the crank case to discharge into the power cylinder when the piston 14 moves to the bottom of its stroke.

40 A port 38 formed in the piston wall, is adapted to register with the lower end of the by-pass port 37 when the piston is at the bottom of its stroke, and the top of the piston is adapted to open the upper end of the 45 port 37 at the same time. An exhaust port 39 is located opposite the port 37 and is adapted to permit of the exhaustion of the major portion of the products of combustion when the piston 14 has moved down- 50 wardly to uncover the opening of the port 39.

The exhaust valve 26 reciprocating in the chamber 26^a formed in the casing 27 extends into the exhaust port 39 and blocks the port so that when the port is opened by the piston 55 14, the pressure of the exploded charge will force the valve 26 upwardly thereby entirely opening the exhaust passage 39. At the same time that the valve 26 is driven upwardly, an auxiliary exhaust port 40, 60 formed in the walls of the cylinder, and which communicates at its outer end with the port 39, and at its inner end with the interior of the cylinder 11, at a point about half way between the exhaust port 39 and

the top of the cylinder, is also opened. The 65 valve 26 is provided at its upper end with a stem 41, adjustment nuts 42, and a spring 43 which is located between the adjustment nuts 42 and a shoulder formed at the bottom of a recess 44 formed in a cap 45 closing the 70 top of the exhaust valve chamber 26^a. This spring 43 is of such a tension that it will balance the weight of the valve 26 so that the valve may be readily opened or closed upon slight pressure being exerted on its bottom 75 face or on its top face. In order that the valve may be kept closed except during the period of exhaust, a small port 46, is formed in the upper end of the cylinder and communicates with the interior thereof and with 80 the valve chamber 26^a. This permits the pressure of compression and explosion to enter the chamber 26^a and force the valve upon its seat.

In constructing my engine I preferably 85 locate the power and supply cylinders at an angle to one another and by attaching the connecting rods 15 and 18 to the single crank pin 20, I am enabled to operate my engine in such a manner that the supply 90 piston 17 will move on both its up stroke and its down stroke, somewhat in advance of the power piston 14. The reason for this differential movement of the supply and power pistons will be hereinafter more fully 95 described.

In operation; in starting the engine, the crank shaft 47 is rotated in a clockwise direction as indicated by the arrow in Fig. 1. This causes reciprocation of the pistons 14 and 17 in their respective cylinders 11 and 12. As rotation is continued, the supply piston 17 moves downwardly upon its induction stroke and in moving downwardly the piston creates in the upper end of the supply cylinder 12 a partial vacuum which causes inlet valve 21 to be opened to permit a charge of fuel to be drawn into the supply cylinder as shown in Figs. 4 to 6 inclusive. This movement of piston 17 continues 105 until the end of the stroke is reached and the cylinder is completely filled, at which time the piston returns on its upward or compression stroke. As the piston nears the end of its stroke as indicated in Fig. 1, by-pass port 29, by-pass port 30, and port 31 are opened to communication with one another as shown in Figs. 8 to 10 inclusive. This permits of the compressed charge located in cylinder 12 to be discharged through 110 the ports 29, 30 and 31, and because of the high pressure of the gas, to force the valve head 35 upwardly to permit the gas to pass into the valve chamber 32. At the same time that the valve head 35 is raised, the sleeve 115 34 opens the port 33 communicating with the power cylinder as shown in Figs. 8 to 120 125 10 inclusive, and permits the charge of fresh

fuel to be discharged from the supply cylinder into the power cylinder through the communicating ports 29, 30, 31, 32 and 33. In moving upwardly the valve 25 is restrained by a light spring 25^a which seats upon the valve at one end and at its other end engages a cap 24^a adapted to close the valve chamber 32.

After the charge has been delivered to the power cylinder, the valve 25 is permitted to close, since the pressure in the ports and in the power cylinder is then uniform. This closing of the valve stops communication between the port 33 and the chamber 32 by bringing the sleeve 34 to register with the port 33, and the valve head 35 stops communication between the chamber 32 and the port 31 as shown in Figs. 2 to 7 inclusive. At this time during the rotation of the engine crank shaft, power piston 14 continues to move upwardly and closes the port 33, see Figs. 2 and 3. This movement continues until the end of the compression stroke, at which time a spark from the spark plug 23 ignites the charge and drives the power piston downwardly.

As the power piston 14 moves downwardly under the pressure of the exploded charge, the port 33 is uncovered, see Fig. 4, but the sleeve 34 of the valve 25 having closed this port to communication with the valve chamber 32, back firing of the charge into the supply ports and into the supply cylinder is prevented. In addition to this the auxiliary exhaust port 40 is uncovered, see Fig. 5, but this port is also closed, since its opening to the main exhaust port 39 is blocked by the exhaust valve 26. It will be observed that the exhaust valve 26 is held in a closed position with relation to the port 40 by the explosive pressure in the power cylinder 11 communicating through the port 46 to the exhaust valve chamber 26^a, the pressure bearing upon the upper end of the exhaust valve to retain it in its closed position.

Near the end of the downward stroke of the power piston, the main exhaust port 39 is opened and the exhaust gases are permitted to pass into the port 39 and out of the power cylinder, see Fig. 6. At this time the exhaust gases act upon the under face of the balanced exhaust valve 26 and cause this valve to move upwardly to open the auxiliary exhaust port 40. This movement of the exhaust valve is permitted because of the increased pressure on its under face which overbalances the decreased pressure on its upper face. At the end of the power stroke of the piston 14 the port 37 is opened at its upper end by the piston and at its lower end by the port 38 in the piston wall as shown in Fig. 6. This permits air from the crank case to rush through the port 38, port 37, and against the deflector 36. This

deflector directs the charge of air upwardly 65 toward the top of the cylinder and acts to force the exhaust gases outwardly through the main exhaust port 39 and auxiliary exhaust port 40. The air in the crank case 13 at the time of the opening of the port 37, 70 having been compressed because of the simultaneous downward movement of both the supply and power pistons, acts to give the air compressed in the crank case, a decided puff to send it into the head of the 75 cylinder to act as a cushion which will force the remaining exhaust gases out of the ports 39 and 40. This exhaustion of the burnt gases continues after the ports 37 and 39 have been closed by the piston 14 in its upward movement, because the auxiliary exhaust port 40 still remains open, as shown in Figs. 7 and 8. At the time however, that the exhaust port 40 is closed by the piston 14 in its upward movement, compression of 80 the air contained in the upper end of the cylinder 11 causes pressure to be exerted through the port 46 and chamber 26^a upon the upper face of the exhaust valve 26. This causes the valve to seat and to close the 90 port 40 to communication with the main exhaust port 39, see Figs. 9 and 10. Previous to this the supply piston is moved downwardly during the downward movement or power stroke of piston 14. This causes the 95 inlet valve 21 to open and to permit the supply cylinder 12 to fill with a fresh charge of fuel. Upon the return movement of the power piston 14 the supply piston 17 also returns to compress the charge located in 100 the supply cylinder, so that when the auxiliary exhaust port 40 in the power cylinder is closed and before the power piston 14 closes the supply port 33, in the power cylinder, the supply ports 29, 30, and 31 have been 105 brought to register with one another to permit the highly compressed charge to enter the ports, to lift the valve head 35 from its seat in the chamber 32, to lift the sleeve 34 from the port 33, and to thereby 110 permit the charge to rush into the power cylinder under compression. As the supply piston 17 has now been brought to the end of its stroke, the power piston has a portion of its stroke to complete. This permits the 115 power piston to close the port 33 and to further compress the charge of gas located in the power cylinder. At the point where the fresh charge is fully compressed the charge is exploded by a spark from the 120 spark plug 23 and the previously described cycle of operations again occurs.

In constructing my engine I preferably locate the respective supply and power cylinders at the angle of 30 degrees to one 125 another for the purpose of giving the respective supply and power pistons the differential action previously mentioned. This

differential action gives the supply piston a somewhat different movement from the power piston in that the supply piston will be constantly moved in advance of the power piston.

In the embodiment illustrated in the drawings, the 30 degree position of the cylinders from one another, will give the supply piston a differential movement of $\frac{1}{3}$ of a stroke in advance of the power piston. This is true, because when the crank shaft 47, crank pin 20, crank pin 20^a, and the axis of the supply cylinder are in alinement with each other, the crank shaft must rotate through an angle of 30 degrees to bring the crank pin 20, crank shaft 47, and the axis of the power cylinder 11 into alinement with each other. This 30 degree rotation is $\frac{1}{3}$ of the 180 degree rotation of the crank shaft, which corresponds to one complete stroke of either of the pistons. It will thus be seen that when the supply piston 17 is at the end of its upward stroke, and has discharged the contents of the supply cylinder 12 into the power cylinder 11, the power piston 14 has $\frac{1}{3}$ of its stroke to complete. At the time of the completion of the upward stroke of the power piston, the supply piston has moved downwardly $\frac{1}{3}$ of its induction stroke, the crank shaft at this time having rotated through the previously described angle of 30 degrees. This same differential action of the pistons is true at the bottom of their strokes, the supply piston 17 at this point also having been moved to the end of its stroke, and back again upon its return stroke before the power piston 14 arrives at the end of its downward stroke. The purpose of this differential action is to permit the fresh charge to be discharged into the power cylinder before the power piston has arrived at the end of its upward or compression stroke previous to the exploding of the charge. In addition to this the purpose of discharging the fresh charge into the power cylinder previous to the completion of the upward stroke of the power piston, permits the valve 25 to close and thereby close communication of the ports 31, 30, 29 with the cylinder 12, so that it will be impossible for back firing to occur in the supply cylinder. It will be observed that the auxiliary inlet valve 25, is a valve of the semi-balanced type, since an aperture 25^b has been provided in the upper portion of the valve for equalizing the pressure upon the upper and lower faces of the upper portion. This permits the spring 25^a to close the valve 25, since it will not have to overcome pressure in the ports 31 and 32, the pressure of gas above the valve being equal to that below the valve.

Having thus described my invention, what I claim is:

1. In combination in an internal combustion engine a supply cylinder having an inlet and a supply port formed therein, a power cylinder having a supply port, a main exhaust port, an auxiliary exhaust port, and an air supply port formed therein, said second mentioned supply port communicating with said first mentioned supply port and located above said main and auxiliary exhaust ports, said auxiliary exhaust port communicating with said main exhaust port, said main exhaust port being located below said auxiliary exhaust port, a supply piston reciprocally mounted in said supply cylinder, a power piston reciprocally mounted in said power cylinder and adapted to open and close said supply port, said auxiliary exhaust port, said air supply port being located opposite said main exhaust port and adapted to be opened when said main exhaust port is opened by said power piston, an inlet valve adapted to open said power cylinder supply port when said supply piston forces a charge from said supply cylinder into said power cylinder through said supply ports, and to close when said power cylinder supply port is closed by said power piston, and an exhaust valve adapted to close said auxiliary exhaust port and adapted to be opened by the pressure of the exhaust gases when said main exhaust port is opened by said power piston.

2. An internal combustion engine comprising a supply cylinder having inlet and supply ports formed therein, a power cylinder having supply and exhaust ports formed therein, the supply ports of both cylinders having a communicating passage, a valve located in the passage and adapted to permit discharge of gas from said supply cylinder to said power cylinder, said valve having a head adapted to close the supply port of the supply cylinder and to open the supply port of the supply cylinder when discharge pressure from the supply cylinder exists beneath the head, and a sleeve adapted to close the supply port of the power cylinder when the valve head is in its normal position, and to open the supply port of the power cylinder when the valve head is moved to its open position.

3. In an internal combustion engine the combination of a supply cylinder, a power cylinder, a piston reciprocally mounted in the power cylinder, said cylinders having communicating supply ports, a valve located between the supply ports and adapted to open during discharge from said supply cylinder to said power cylinder, said valve comprising a head adapted to close the supply cylinder supply port, and a sleeve adapted to close the power cylinder supply port, said power cylinder having a main

exhaust port formed therein below the supply port and adapted to be closed by the power piston, said power cylinder having an auxiliary exhaust port formed therein intermediate its supply and main exhaust ports, and an exhaust valve adapted to close the auxiliary exhaust port while the main exhaust port is closed.

In testimony whereof, I have hereunto subscribed my name this 20th day of Feb- 10
ruary, 1915.

VICTOR ROSENHAGEN.
